US0D1096812S

(12) **United States Design Patent** (10) **Patent No.:** **US D1,096,812 S**
(45) **Date of Patent:** **** Oct. 7, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Elbert D. Chen**, Cupertino, CA (US);
Michael Charles Evashevski, San
Francisco, CA (US); **Fernando**
Augusto Teixeira Da Cunha
Albuquerque, Cupertino, CA (US)

(73) Assignee: **Apple Inc.**, Cupertino, CA (US)

(**) Term: **15 Years**

(21) Appl. No.: **29/957,551**

(22) Filed: **Aug. 14, 2024**

Related U.S. Application Data

(63) Continuation of application No. 29/909,532, filed on
Aug. 7, 2023, now Pat. No. Des. 1,040,172, which is

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing the claimed design.

The peripheral dashed broken lines illustrate a display screen or portion thereof, and form no part of the claimed design.

**1 Claim, 1 Drawing Sheet
(1 of 1 Drawing Sheet(s) Filed in Color)**

Related U.S. Application Data

a continuation of application No. 29/862,104, filed on Dec. 6, 2022, now Pat. No. Des. 994,702, which is a continuation of application No. 29/808,550, filed on Sep. 21, 2021, now Pat. No. Des. 974,397, which is a continuation of application No. 29/768,516, filed on Jan. 29, 2021, now Pat. No. Des. 933,711, which is a continuation of application No. 29/692,959, filed on May 29, 2019, now Pat. No. Des. 913,324.
